PRESS FOR ATTACHING RUBBER TRIM

James P. Marshall, Coventry, R. I., assignor, by
mesne assignments, to Goodyear Footwear
Corporation, a corporation of Delaware

Application March 11, 1936, Serial No. 68,190

2 Claims. (Cl. 12—52)

This invention relates to improvements in a press for attaching rubber trim.

In the manufacture of footwear such as tennis shoes, it is customary to apply to the outside of the upper various pieces of rubber trim or foxings such as an angle patch, an eyelet stay, and an arch strap. In some cases these are stitched to the upper and in other instances they are secured by adhesion.

10 It is an object of this invention to provide a press for attaching such rubber trim to the upper by adhesion and to this end it is a further object to provide a press having two plungers for applying suitable pressure, cooperating dies 15 for determining the shape and size of the trim, and heating means with automatic control for determining the proper heat to be used during the period in which the pressure is applied. Other 20 objects and features of the improved apparatus will become apparent as the detailed description develops.

The best mode in which it has been contemplated to apply the principles of the invention is shown in the accompanying drawings, but these 25 are to be taken as merely illustrative and it is intended that the patent shall cover by suitable expression in the appended claims whatever features of patentable novelty exist in the invention disclosed.

30 In the accompanying drawings:

Figure 1 is a front elevation of a press constructed in accordance with the principles of this invention;

Figure 2 is a side elevation as seen from the 35 left of Figure 1;

Figure 3 is a vertical section, as on line 3—3 of Figure 1, through one control valve;

Figure 4 is a vertical section, as on line 4—4 of Figure 1, through the other control valve.

40 Figure 5 is a plan view, taken as on line 5—5 of Figure 1;

Figure 6 is a vertical section as on line 6—6 of Figure 5; and

Figure 7 is a perspective, partly in section as though taken on line 6—6 of Figure 5 and inverted, showing a portion of the upper and trim applied thereto.

Referring more particularly to the drawings, the press comprises a base 1 to which are secured die blocks 2 and 3. Each block is provided with an upstanding die 4, 5 on its top face, and as here shown these dies are of the same design, one portion 4a, 5a determining an eyelet stay and the other portion 4b, 5b determining an arch strap. It is, of course, to be

understood that the two dies need not be of the same configuration but that one may be shaped to determine one kind of trim and the other die differently shaped to determine a different kind of trim. Within the body of each 5 die block is one or more heating elements 6, here shown as electrical elements, the supply of heat to which is controlled by a suitable heat actuated and heat responsive device 7 of any suitable design.

10 Also mounted on the base 1 at the rear of the die blocks are standards 8, 9 each of which supports a cylinder 10, 11 respectively. In each cylinder is a piston 12, 13 and on the rod 14, 15 of the latter, which extends downward through 15 a suitable packing box 16, 17 is a pressure plate 18, 19. Plate 18 is arranged to overlie die 4 on the block 2 and plate 19 similarly overlies the die 5. Upon the application of pressure to the upper sides of the pistons the plates are forced 20 toward the dies and when pressure is applied to the underside of the pistons the plates are withdrawn from the dies.

In applying a trim to an upper of a shoe, a section A of gum rubber sheet material is laid 25 on the die, as seen in Figure 5. This section is of greater extent than the die. The upper B is then laid on the said section A of sheet material, being positioned relative to the die so that one edge B1 of the upper registers with an edge 30 5c of the die (see Figure 6). The edges of the die, as seen at 5d are slightly raised to afford a sort of cutting edge which penetrates into the rubber as the pressure is applied to the upper surface of the upper. The plate overlying the 35 position upper is now ready to be lowered into contact therewith, and this is effected by a novel combination of piping and control valves, so correlated as to protect the operator from danger of his or her hands being under the descending 40 pressure plate.

Fluid pressure such as compressed air is supplied through a pipe 20 and leads through a branch 21 to one control valve 22. This is so-called three-way valve. When the operating 45 handle 23 of this valve is in its upright position, as shown in Figure 1 (and as seen partly in full lines in Figure 3), the valve proper is set so that its main diametrical port 22a connects pipe 21 with a pipe 24. From the latter two 50 branches extend, one branch 25 leading to the lower portion of cylinder 10 and the other branch 26 leading to the upper side of cylinder 11. With the valve 22 thus positioned, that is with its diametrical port connecting pipe 21 with pipe 24, 55

and with its radial port 22b closed by the valve casing, the fluid pressure will pass to the underside of piston 12 and to the upper side of piston 13, thereby tending to lift the pressure plate 18 and to depress the other plate 19.

Branch pipe 28 from the main fluid supply pipe 20 leads to a second control valve 29. This is of the same design as the other, but its operating handle 30 is so mounted with respect to the valve proper that when the handle is vertical, as seen in Figure 1, (and as shown partly in full lines in Figure 4), the fluid supply in pipe 28 is cut off and the diametrical port 29a is in register with a vent 29c in the wall of the valve. The radial port 29b is in register with a pipe 31, from which one branch 32 leads to the upper portion of cylinder 10 and another branch 33 leads to the lower portion of cylinder 11. Thus with valve 22 set to admit pressure to one end of the cylinders, the other valve 29 is set to permit fluid to escape from the opposite ends of the cylinders.

When the control handles are moved to their horizontal positions, as indicated in dotted outline in Figures 3 and 4, the diametrical port 22a of valve 22 will register with vent 22c and the radial port will be opposite the end of pipe 24. Thus pressure from both cylinders may escape through branches 25 and 26 and pipe 24. When handle 30 of valve 29 is horizontal, the diametrical port 29a will connect pipe 28 and pipe 31 and pressure will flow through branches 32 and 33 to the cylinders. Radial port 29b will be closed by the wall of the valve.

In the operation of the press, both valves should be shifted together and thus the control of these valves causes the operator, after placing the rubber section A and the upper B on one die, to reach with both hands for the valve handles 23 and 30. Both handles are then thrown together from vertical to the horizontal position (or vice versa) and as a result the pressure plate which is down will move upward and the one which is up will move downward.

As the descending plate engages the upper it is pressed firmly against the gum rubber section and the latter pressed firmly against the die. Since the latter is properly heated, the com-

bined effect of this heat and the pressure causes that portion of the gum rubber section in contact with the die to adhere firmly to the upper. Overheating of the rubber is prevented by the automatic heat responsive control devices 1. 5 While an upper is under pressure under one plate, the upper which has just previously been acted upon by the other plate and die can be removed. The excess of the rubber section outside the lineal indentation made by the raised 10 edges 5d of the die can be readily torn off by the operator, leaving the trim C firmly in place on the upper B as seen in Figure 7. By suitably indenting the upper face of the die (indicated by dotted lines on die 4 in Figure 5) slight 15 protuberances C may be formed on the trim to simulate stitches.

I claim:

1. A press for attaching rubber trim to a shoe upper comprising, in combination, a pair of dies 20 of configuration conforming to the trim to be attached; means for heating each die to a pre-determined temperature; pressure plates arranged to be moved toward and from said dies; pressure actuated means for moving each of said plates; and means controlling the application of pressure upon the last said means to the end that as one plate moves toward its die, the other plate is withdrawn therefrom.

2. A press for attaching rubber trim to a shoe 30 upper comprising, in combination, a pair of dies of configuration conforming to the trim to be attached; pressure plates arranged to be moved toward and away from said dies; a cylinder with piston therein for moving each pressure plate; 35 and a pair of valves controlling the admission and escape of fluid to said cylinders; said valves being so organized and connected to said cylinders that when one valve is set to admit fluid to one cylinder to cause its pressure plate to move toward its respective die, fluid is simultaneously admitted to the other cylinder to cause its pressure plate to move away from its respective die, and fluid is permitted to escape from the end of each cylinder toward which its piston is being 40 moved.

JAMES P. MARSHALL.
